CLAIM

The ornamental design for a trapper hat, as shown and described.

DESCRIPTION

FIG. 1 is a left side perspective view of a trapper hat with the earmuffs shown in the upward position;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a left side perspective view of the trapper hat in an alternate position with the earmuffs shown in the downward position.

The broken lines illustrate environmental structure and form no part of the claimed design. The “dash-dot-dash” broken lines shown in FIG. 8 illustrates the bounds of the claimed design.
